UNITED STATES PATENT OFFICE.

THOMAS P. MOORE, OF READING, PENNSYLVANIA, ASSIGNOR TO ABRAHAM LINCOLN FRAME, OF READING, PENNSYLVANIA.

SEWER VENT-BOX.

992,377.

Specification of Letters Patent.

Patented May 16, 1911.

Application filed March 2, 1911. Serial No. 611,746.

To all whom it may concern:

Be it known that I, THOMAS P. MOORE, a citizen of the United States, residing at Reading, in the county of Berks and State of Pennsylvania, have invented certain new and useful Improvements in Sewer Vent-Boxes, of which the following is a specification.

This invention relates to improvements 10 in sewer vent boxes and the object is to provide a vent box of comparatively simple construction and to the interior of which access may easily be had.

The invention is more fully described in 15 the following specification and clearly illustrated in the accompanying drawing, in which:

Figure 1 is a vertical, central sectional view. Fig. 2 is a plan view of my vent box. 20 The numeral 1 designates the sewer pipe connection. This connection is formed with an external thread 2.

The numeral 3 designates the inner casing, and this casing is formed with a series of 25 buttons 4 on its inner surface, which buttons are adapted to be engaged by the convolutions of the thread 2 when the member 1 is screwed into the casing 3. The member 3 is also formed with two pairs of lugs 5 near its upper end, at diametrically opposite points, and two like pairs of lugs 5^a 30 near the lower end and in vertical alignment with the upper lugs. The lower lugs are slightly longer than the upper ones.

The casing is formed at its upper end 35 with an inwardly curved flange 6, forming a central opening 7 at the top of the casing.

The numeral 8 designates the outer casing. This is formed with a pair of internal 40 lugs 9, each of which is adapted to enter the space between the upper lugs 5 of the inner casing; near the lower end of the casing 8 a second pair of like lugs 9^a is formed, which in turn are adapted to enter the 45 spaces between the lugs 5^a.

The lugs 9 and 9^a are preferably formed with tapered side walls, so that they will wedge between the lugs 5 and 5^a when in position as shown in Fig. 1.

50 The upper end of the casing 8 is formed

with a flange 10 and is slightly enlarged, and in this enlarged portion I place a cover plate 11. This plate is provided with a locking tongue 12 adapted to enter an opening 13 in the wall of the casing 8, and at a 55 point directly opposite the tongue, I provide a fastening screw 14 by means of which the plate is secured in the casing.

The cover plate is perforated, as indicated by numeral 15, and to the under side thereof, at the center, I secure a dome 16, held in position by means of a bolt 17, and this dome extends over the upper end of the inner casing 3, so that any water or soil entering the perforations in the cover plate 60 65 will be shed around the inner casing and will not enter it.

It is evident that the venting of the sewer to which my vent box is attached will be free, and that to secure access to the inside 70 of the vent box, it will be only necessary to remove the screw 14 and the cover may be removed, together with the dome.

Having thus fully described my invention, what I claim and desire to secure by Letters 75 Patent is:

In a vent box for sewers, the combination with a sewer pipe connection threaded externally, an inner casing formed with an inwardly flanged upper end, internal buttons 80 arranged to engage the convolutions of the thread on the pipe connection and four pairs of diametrically opposite lugs on its outer surface, of an outer casing formed with registering lugs adapted to enter the spaces 85 between the pairs of lugs on the inner casing, a perforated cover plate for the outer casing, said plate having a locking tongue adapted to engage the casing and means for securing the cover plate to the casing, and 90 a dome secured to the under side of the casing adapted to cover the upper open end of the inner casing.

In testimony whereof I affix my signature, in presence of two witnesses.

THOMAS P. MOORE.
